CONTROL SYSTEM FOR A PUMP

David B. Puryear, St. Joseph, Mich., assignor to The Bendix Corporation, St. Joseph, Mich., a corporation of Delaware

Filed Aug. 13, 1962, Ser. No. 216,593
5 Claims. (Cl. 103—162)

This invention relates to a pump, and more particularly to a control system for a variable displacement pump. Automatic controls for variable displacement pumping structures are in wide use. The most commonly utilized systems of automatic control are those in which the pumping mechanism is either flow compensated or pressure compensated. A flow compensated system is one in which the displacement of the pumping mechanism is automatically reduced as the fluid output tends to exceed a predetermined maximum or automatically increased as the fluid output tends to fall below a predetermined minimum. A pressure compensated system is one in which the displacement of the pumping structure is reduced as the pressure in the outlet line of the device tends to exceed a predetermined maximum.

It is an object of the invention to provide a variable displacement pump with a flow control for maintaining constant pump output.

It is another object of the invention to provide a variable displacement pump with a control system which not only has a flow control for maintaining constant pump output but also a pressure control for controlling the maximum pressure in the pump outlet.

A further object of the invention is to provide a variable displacement pump with the combination of a flow control and pressure maintaining control wherein the response of one control does not affect the response of the other control.

An over-all object of the invention is to achieve the above objects with structure which is simple and economical to produce.

Further objects and advantages of the present invention will become apparent from the following description, reference being made to the accompanying drawings wherein a preferred form of the present invention is shown. In the drawings:

FIGURE 1 is a section view illustrating a flow control valve and a pressure control valve in neutral positions;

FIGURE 2 is a view illustrating the flow control valve in one of its operating positions while the pressure control valve is in neutral position;

FIGURE 3 is a view illustrating the flow control valve in a different operating position while the pressure control valve is in neutral position; and

FIGURE 4 is an illustration of the flow control valve and the pressure control valve in operating positions.

Referring to FIGURE 1, there is shown a pump rotor 10 mounted for rotational movement relative to a port plate 12. Pistons 14 are displaceable within the rotor and the stroke of the pistons are controlled by the angle of the swash plate 16, which angle is controlled by slidable movement of a servo piston 18 within a cylinder bore 20. A pair of trunnion balls 24 (one of which is shown) defines an axis about which the swash plate rotates. Rotation of the swash plate is effected by movement of the piston 18 which movement is transferred to the swash plate through a thrust link 22. The interior of the rotor 10 and the association of the pistons 14 and port plate 12 therewith may be of any well known construction as for instance the structure illustrated in applicant's copending application U.S. Serial No. 778,538 filed December 5, 1958 (common assignee), now U.S. Patent No. 3,070,031. An outlet passage 26 is connected to an outlet port of

2

the port plate 12 and has a restriction 28 therein. The passage 26 upstream of the restriction 28 is communicated to the one end 30 of a slidable flow control valve spool 32 and to one end 34 of a slidable pressure control valve spool 36 by passages 38 and 40 respectively. The passage 26 downstream of the restriction 28 is connected to the other end 45 of the flow control valve spool 32 and the chamber 33 by a passage 39. The interior 42 of the pump body is communicated by a passage 44 to a drain and is maintained at low pressure. The low pressure in the interior 42 is communicated to the other end 46 of the pressure control valve spool 36 and to a chamber 48 by a passage 50 and a passage 52 communicates the low pressure in chamber 48 to the bore 29. A passage 54 interconnects the flow control valve spool and pressure control valve spool bores 29 and 35 and the passage 56 interconnects the pressure control valve spool bore 35 with the servo piston cylinder bore 20.

The volume of flow across the restriction 28 may be determined as follows:

Let:

Q =the volume of fluid passing through said restriction at a given rate of time

25 A =the area of the orifice 28

C =the coefficient of discharge of the restriction

g =gravity force

ΔP =the pressure drop across the restriction 28

Then:

$$Q=AC\sqrt{2g\Delta P}$$

$$Q=AC\sqrt{2g\Delta P}$$

since A, C, and $2g$ remain constant, $AC\sqrt{2g}$ may be replaced by K which equals a constant. It then follows that:

$$Q=K\sqrt{\Delta P}$$

In other words the quantity or flow varies as the square root of the pressure drop across the restriction or is a function of the pressure drop across the orifice 28. Therefore, for a given rate of flow there will be a given pressure drop across the orifice.

Since the pressure downstream of restriction 28 in passage 26 is communicated to the end 45 of the flow control valve spool 32 by passage 39 and the pressure upstream of restriction 28 in passage 26 is communicated to the end 30 of the flow control valve spool 32 by passage 38, the pressure drop across restriction 28 may be sensed by the valve 32 thereby controlling the output flow of the pump in a manner to be described hereinafter.

The slidable flow control valve spool 32 has a pair of spaced lands 58 and 60 and another land 62 spaced from the land 58. As can be seen, communication between the passages 52 and 38 are always cut off from each other by the lands 58 and 60 no matter in which direction the valve spool 32 is moved. In the neutral position illustrated in FIGURE 1, the land 58 separates passage 52 from passage 54 and the land 60 separates the passage 38 from passage 54. With reference to FIGURE 2, when the valve member 32 is in an operating position shown therein the land 58 communicates passage 52 with passage 54 and when the valve member 32 is in an operating position as shown in FIGURE 3 the passage 38 is communicated with passage 54.

65 The pressure control valve spool 36 has a pair of spaced lands 64 and 66. In the normal position of valve spool 36 illustrated in FIGURE 1, it can be readily seen that the land 64 communicates the passage 54 with passage 56 and separates passages 54 and 56 from the passage 40; passage 40 being always separated from passage 54. When the valve spool 36 is in an override position as shown in FIGURE 3 passage 54 is separated from passages 56 and

40 by the land 64 and passage 40 is communicated with passage 56 by the land 66.

Springs 68 are compressed between a seat 70 of their respective valve spools and a retainer cup 72 for biasing their respective valve spools against the upstream pressure acting on the ends 30 and 34 of their respective valve spools. The compression of the springs 68 are adjustable by turning an adjusting screw 74 and renders possible the operation of the valve members 32 and 36 for different values of constant flow desired and maximum pressure desired.

Operation

Referring to FIGURE 1, assuming that the pressure drop across the restriction 28 corresponds to that set by the flow control valve member 32 for the normal position and the pressure upstream in passage 26 is below the maximum set for the pressure control valve 36, then the servo piston 18 remains in its set position since the pressure acting thereon is contained within passages 56 and 54 and bore 35.

Referring to FIGURE 2 and assuming that the pressure drop across the restriction 28 is less than that allowed by the flow control valve spool 32 (therefore flow has dropped) and the upstream pressure 26 is less than the maximum allowed by the pressure control valve spool 36, then the combined forces resulting from the downstream pressure and the spring 68 acting on the end 45 of the flow control valve spool 32 will be greater than the force resulting from the upstream pressure acting on the end 30 of the flow control valve member 32 thereby resulting in the valve member 32 being biased downwardly and communicating passage 52 to passages 54 and 56 to the servo piston 18; the passage 54 being communicated to passage 56 since the valve member 36 is still in normal position. The pressure in chamber 20 will bleed via the passage 52, chamber 48 and passage 50 to the drain resulting in the piston 18 being lowered and the swash plate angle being raised to increase the stroke of the pistons and therefore the output of the pump.

Now referring to FIGURE 3 and assuming that the pressure drop across the restriction 28 is greater than that allowed by the flow control valve spool 32 (therefore flow has increased) and the upstream pressure in passage 26 is less than the maximum allowed by the pressure control valve spool 36, then the upstream pressure in passage 38 acting upon the end 30 of slidable flow control valve spool 32 will produce a force greater than the force of the downstream pressure and spring 68 acting on the other end 45 of the flow control valve spool 32 to bias the valve spool 32 upwardly to communicate the passage 38 with the passage 54. Upstream pressure will be communicated to the passage 56 and to the servo piston 18 biasing the piston upwardly to lower the swash plate angle and the output of the pump since the pressure control valve spool 36 is still in normal position.

Assuming there is a set amount of flow and therefore the pressure drop across the restriction 28 is as allowed by the flow control valve spool 32 and the upstream pressure in passage 26 is greater than that allowed by the pressure control valve spool 36, then the pressure control valve spool 36 will be biased upwardly thereby communicating the passage 40 with the passage 56 for moving the piston 18 upwardly and lowering the swash plate angle and the output of the pump.

Assuming that flow has increased and therefore there is too great a pressure drop across the restriction 28 and that the upstream pressure in passage 26 is greater than that allowed by the pressure control valve 36, then both control valves will be biased upwardly with each control valve tending to help each other since the result of their movements would be to communicate the upstream pressure in passages 38 and 40 with the passages 54 and 56 respectively which lead to the chamber 20 for biasing the

servo piston 18 upwardly and lowering the swash plate angle and the output of the pump.

Referring to FIGURE 4 and assuming that flow has dropped and therefore the pressure drop across the restriction is less than that allowed by the flow control valve member 32 and the upstream pressure in passage 26 is greater than that allowed by the pressure control valve spool 36, then the flow control valve 32 will be biased downwardly communicating the low pressure passage 52 with passage 54. However, the pressure control valve 36 will override the flow control valve since the upstream pressure in passage 40 acting on the end 34 of the pressure control valve spool 36 will produce a greater force than the combined force produced by the low pressure in chamber 48 and the spring 68 acting on the end 46 of the valve spool 36 thereby moving the pressure control valve spool 36 and cutting off communication between passages 54 and 56 by the land 64 and communicating the passage 40 and therefore the upstream pressure with the passage 56 and the servo piston 18 by land 66. The piston 18 will be raised thereby reducing the swash plate angle and the stroke of the pistons and the output of the pump as called for by the pressure control valve instead of increasing the angle of the swash plate and raising the output of the pump as called for by the flow control valve. When the flow control valve 32 is attempting to communicate the chamber 20 with the low pressure passage 52 and the pressure control valve 36 is trying to communicate the upstream pressure passage 40 with the passage 56 and the chamber 20, there may be a slight period wherein passages 54 and 56 are communicated with each other before the land 64 cuts off such communication. However, if such communication is effected the lag before land 64 cuts off such communication is not considered to be critical.

Thus, it can be seen that applicant has achieved a control system wherein the system may control flow produced by the pump regardless of an increase in speed of rotation of the rotor or a decrease in speed of rotation of the rotor and also has a pressure control which operates independently of the flow control and overrides the flow control when pressure in the system exceeds a predetermined amount. Of course, the flow control will operate to maintain a constant flow only during the period when certain conditions reside in the pump. The pump rotor must be rotating at within a certain minimum or maximum speed and the pressure must be within a certain minimum or maximum value in addition to some other minor variable before the pump will be capable of giving a certain flow required.

While the form of the embodiment of the invention as herein disclosed constitutes a preferred form, it is to be understood that other forms may be adopted, all coming within the scope of the claims which follow.

I claim:

1. The combination of a variable displacement pump and a control system therefor, comprising: fluid operated control means for varying the output of said pump; said pump having an outlet port; first passage means communicating with said outlet port; a flow restriction in said first passage means separating said first passage means into two portions; first valve means communicating with both portions of said first passage means; second passage means communicating said first valve means with said fluid operated control means; second valve means located in said second passage means and communicating with said first passage means; third passage means communicating a low pressure source to said first valve means; said first valve means being so arranged and constructed that it communicates with said third passage means with said second passage means in one operating position, communicates said first passage means with said second passage means in a second operating position, and cuts off said second passage means from said first passage means and said third passage

means in a third operating position; said second valve means being so arranged and constructed that it communicates said first valve means with said fluid operated control means in a normal position and cuts off communication between said first valve means and said fluid operated control means while communicating said first passage means to said fluid operated control means in an override position, said first valve means being responsive to the pressure differential across said flow restriction; said second valve means being responsive to pressure beyond a predetermined limit in one of said portions of said first passage means; whereby said fluid operated control means will be controlled by said first valve means when the pressure in said one portion of said first passage means is below said predetermined limit and said fluid actuated control means will be controlled by said second valve means when the pressure in said one portion of said first passage means is beyond said predetermined limit.

2. The combination of a variable displacement pump and a control system therefor, comprising: fluid operated control means for varying the output of said pump; said pump having an outlet port; first passage means communicating with said outlet port; a flow restriction in said first passage means; first valve means communicated with said first passage means upstream and downstream of said flow restriction; second passage means communicating said first valve means with said fluid operated control means; second valve means located in said second passage means and communicated with said first passage means upstream of said flow restriction; third passage means communicating a low pressure source to said first valve means; said first valve means being so arranged and constructed that it communicates said third passage means with said second passage means in one operating position, communicates said first passage means upstream of said flow restriction with said second passage means in a second operating position, and cuts off said second passage means from said first passage means and said third passage means in a third operating position; said second valve means being so arranged and constructed that it communicates said first valve means with said fluid operated control means in a normal position and cuts off communication between said first valve means and said fluid operated control means while communicating said first passage means upstream of said flow restriction to said fluid operated control means in an override position; said first valve means being responsive to the pressure differential across said flow restriction; said second valve means being responsive to pressure beyond a predetermined limit upstream of said flow restriction to move from said normal to said override position; whereby said fluid operated control means will be controlled by said first valve means when the pressure upstream of said restriction is below said predetermined limit and said fluid operated control means will be controlled by said second valve means when the pressure in said first passage means upstream of said restriction is beyond said predetermined limit.

3. The combination of a variable displacement pump and a control system therefor, comprising: fluid operated control means for varying the output of said pump; said pump having an outlet port; a first passage means communicating with said outlet port; a flow restriction in said first passage means; first valve means communicated with said first passage means upstream and downstream of said flow restriction; second valve means communicated with said first passage means upstream of said flow restriction; second passage means interconnecting said first and second valve means, third passage means communicating said second valve means with said fluid operated control means; fourth passage means communicating a low pressure source to said first valve means; said first valve means being so arranged and constructed that it communicates with said fourth pas-

sage means with said second passage means in one operating position, communicates said first passage means upstream of said flow restriction with said second passage means in a second operating position, and cuts off said second passage means from said first passage means and said fourth passage means in a third operating position; said second valve means being so arranged and constructed that it communicates said second passage means with said third passage means in a normal position and cuts off communication between said second passage means and said third passage means while communicating said first passage means upstream of said flow restriction to said third passage means in an override position; said first valve means being responsive to the pressure differential across said flow restriction; said second valve means being responsive to pressure beyond a predetermined limit upstream of said flow restriction to move from said normal to said override position; whereby said fluid operated control means will be controlled by said first valve means when the pressure upstream of said restriction is below said predetermined limit and said fluid operated control means will be controlled by said second valve means when the pressure in said first passage means upstream of said restriction is beyond said predetermined limit.

4. The combination of a variable displacement pump and a control system therefor comprising: fluid operated control means for varying the output of said pump, said pump having an outlet port, a first passage means communicated with said outlet port, a flow restriction in said first passage means, a first bore having a first movable valve member therein, second passage means communicating pressure downstream of said restriction to one end of said first movable valve member for biasing the valve member in one direction, third passage means communicating pressure upstream of said restriction to the other end of said valve member biasing said first valve member in the opposite direction, a second bore having a second movable valve member thereon, fourth passage means communicating said first bore with said second bore, fifth passage means for communicating said first bore with low pressure, said first valve member closing off said fourth passage means from said fifth and third passage means when in neutral position and said fifth and third passage means from each other at all times, said first movable valve member communicating said fourth and third passage means when moved in said opposite direction and communicating said fourth and fifth passage means when moved in said one direction, sixth passage means communicating said second bore to said fluid operated control means, seventh passage means communicating said upstream pressure with one end of said second valve member urging the same in an override position, means for biasing said second valve member into a normal position, said second valve member when in said override position communicating said sixth and seventh passage means and cutting off communication between said fourth passage means and said sixth passage means and when in said normal position cutting off said sixth and seventh passage means communication and communicating said fourth passage means with said sixth passage means, whereby said fluid operated control means will be controlled by said first valve member when the pressure upstream of said restriction is below the limit determined by said biasing means and said fluid operated control means will be controlled by said second valve member when the pressure in said first passage means upstream of said restriction is beyond the limit determined by said biasing means.

5. The combination of a variable displacement pump and a control system therefor comprising: fluid operated control means for varying the output of said pump, said pump having an outlet port, a first passage means communicated with said outlet port, a flow restriction in said first passage means, a first bore having a first spool slid-

able therein, second passage means communicating pressure downstream of said restriction to one end of said first spool member for biasing the spool member in one direction, third passage means communicating pressure upstream of said restriction to the other end of said first spool member biasing said first spool in the opposite direction, fourth passage means communicating said first bore with low pressure, a second bore and a second spool slideable therein, fifth passage means communicating said first bore with said second bore, said first spool having a pair of annular lands at said other end and a land spaced from one of said pair of lands defining an annular groove therebetween, said annular groove bridging said fourth passage means and said pair of lands bridging said fifth passage means when said spool is in neutral position, the other of said pair of lands communicating said third and fifth passage means when said spool is moved in said opposite direction and said groove communicating said fourth and fifth passage means when said spool is moved in said one direction, sixth passage means communicating said second bore with said fluid control means, seventh passage means communicating said upstream fluid pressure with one end of said second spool and biasing said spool into an override position, means for biasing said second spool into a normal position, said second spool having a pair of annular lands at said one end thereof and a land spaced from one of said last named pair of lands defining an

5

10

15

20

25

annular groove therebetween which bridges said fifth and sixth passage means when in normal position and when biased substantially into override position, said one of said spaced lands will cut off communication of said fifth and sixth passage means and the other of said spaced lands will communicate said sixth and seventh passage means, whereby said fluid operated control means will be controlled by said first spool member when the pressure upstream of said restriction is below the limit determined by said biasing means and said fluid operated control means will be controlled by said second spool member when the pressure in said first passage mean upstream of said restriction is beyond the limit determined by said biasing means.
